CLAIM

The ornamental design for display screen or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a display screen or portion thereof with graphical user interface showing the new design.

FIG. 2 is a front view of a second embodiment of a display screen or portion thereof with graphical user interface showing the new design.

FIG. 3 is a front view of a third embodiment of a display screen or portion thereof with graphical user interface showing the new design.

FIG. 4 is a front view of a fourth embodiment of a display screen or portion thereof with graphical user interface showing the new design.

FIG. 5 is a front view of a fifth embodiment of a display screen or portion thereof with graphical user interface showing the new design; and,

FIG. 6 is a front view of a sixth embodiment of a display screen or portion thereof with graphical user interface showing the new design.

The broken lines illustrate a mobile device, which is the environment of the design, and which form no part of the claimed design. The dash-dot broken lines in the drawing show the display screen or portion thereof and form no part of the claimed design.

The boundary line is represented as a dot-dash line surrounding the graphical user interface and represents a boundary of the claim.
